(57) **CLAIM**

The ornamental design for a dog garment, as shown and described.

DESCRIPTION

FIG. 1 is a top, front, left perspective view of a dog garment, in condition of use on a dog, showing my new design; FIG. 2 is a top, front, left perspective view of the dog garment of FIG. 1, shown enlarged for clarity of disclosure; FIG. 3 is a top, rear, right perspective view thereof; FIG. 4 is a front elevational view thereof; FIG. 5 is a rear elevational view thereof; FIG. 6 is a left side elevational view thereof; FIG. 7 is a right side elevational view thereof; FIG. 8 is a top plan view thereof; and, FIG. 9 is a bottom plan view thereof.

In FIG. 1, the broken line showing of a dog depicts environmental subject matter only and forms no part of the claimed design. In FIGS. 1-9, the broken line showing of garment fasteners (a zipper and D-rings), a zipper pull and related zipper flaps depicts environmental subject matter only forms no part of the claimed design. In FIGS. 1-9, the broken line showing on the dog garment depicts stitching and forms no part of the claimed design.

1 Claim, 9 Drawing Sheets
